UNITED STATES PATENT OFFICE.

JOSEPH PETER EASTMAN, OF MANITOWOC, WISCONSIN.

CONVEYER APPARATUS.

Application filed June 22, 1920. Serial No. 390,834.

To all whom it may concern:

Be it known that I, JOSEPH PETER EASTMAN, a citizen of the United States, and resident of Manitowoc, in the county of Manitowoc and State of Wisconsin, have invented certain new and useful Improvements in Conveyer Apparatus; and I do hereby declare that the following is a full, clear, and exact description thereof.

10 My invention relates to new and useful improvements in conveying means and has particular reference to a fan conveyer for fluids, most especially for gas from gas producers and the like.

15 The principal object of this invention is to provide a combined conveyer and mixer whereby gas may be simultaneously agitated, commingled and conveyed from one point to another. In this connection I provide a pair 20 of oppositely rotatable propellers which are so constructed and arranged as to move material in a single direction.

25 It is a further object of this invention to provide a simply constructed, readily operated device of this character which can be easily installed and used in connection with various types of machinery.

30 With these general objects in view the invention resides in the novel features of construction, combination and arrangement of parts which will be hereinafter more particularly described and claimed.

In the accompanying drawing:

35 Figure 1 represents a side elevational view of a device constructed in accordance with my invention, and

Figure 2 is a horizontal sectional view taken substantially on the plane of the line 2—2 of Figure 1.

40 Referring more particularly to this drawing, it will be seen that the reference character 1 denotes a two part casing mounted on a suitable base 2 and having an inlet 3 opening into one side wall 4 adjacent the peripheral edge thereof.

An outlet 5 is provided for the casing in its peripheral wall 6 adjacent the opposite flat wall 7, and at a point substantially diametrically opposite the inlet 3. A suitable 50 supply pipe 8 is connected with the inlet 3 and a discharge pipe 9 suitably attached to the outlet 5.

Each of the opposite flat walls 4 and 7 has

a concentrically arranged opening 10, surrounded by a stuffing box 11, these openings 55 10 being adapted to receive shafts 12 and 13. The shaft 12 extends through the wall 4 and has a propeller 14 secured to its inner end within one half of the casing 1, the other shaft 13 which projects through the wall 7 60 being similarly provided with a propeller 15.

The outer ends of the shafts 12 and 13 are connected with suitable means for revolving the same in opposite directions. The blades 16 of the propeller 14 are angled or pitched in the opposite direction to the blades 17 of the propeller 15, and the cross section of each is in the shape of an ogee curve so that although gas or other fluid is sucked into the casing 1, through the inlet 70 3 wherein such blades are rotated, and discharged through the outlet 5, such fluid is considerably agitated and if composed of more than one kind of gas or other material being operated upon the same will be thoroughly commingled. Consequently this invention will be found to be of considerable benefit in conveying the fluid from gas producers and similar machinery. It will be noted that the edges of blades 17 immediately adjacent to flat wall 7 are all in the same plane. The edges of blades 17 on the other end of propeller 15, also, lie in a common plane, excepting that the ends of the blades are cutaway, leaving spaces adjacent 75 the cylindrical wall of the casing. Propeller 14 is shaped in a similar manner.

I claim:

The combination of a cylindrical casing wall, a flat wall rigid therewith at one end thereof, a side wall at the other end thereof, a shaft journalled in said side wall, a propeller rigid therewith, said side wall having an inlet opening therein between said propeller and said cylindrical casing wall, a second shaft journalled to rotate in said flat wall, the blades of said propeller being oppositely disposed, said cylindrical casing wall having an outlet opening therein, adjacent said second propeller.

In testimony that I claim the foregoing I have hereunto set my hand at Manitowoc, in the county of Manitowoc and State of Wisconsin.

JOSEPH PETER EASTMAN.
